FORREST J. COUCH, OF CINCINNATI, OHIO, ASSIGNOR TO THE AMERICAN LAUNDRY MACHINERY COMPANY, OF NORWOOD, OHIO, A CORPORATION OF OHIO.

DOOR-CLAMPING MECHANISM.

Application filed November 27, 1925. Serial No. 71,772.

This invention relates to washing or like machines of the type comprising an outer tub and an inner cylinder, and has particular bearing upon the door arrangement in the outer tub and the provision of a suitable construction in the washer drum itself to facilitate loading and dumping.

Commercial washing or like machines usually comprise an outer tub with a door 10 extending over its upper front quarter and a work receiving cylinder also provided with a door adapted for registration with the door of the tub, whereby the machine may be loaded and unloaded.

15 The present invention relates to a washing or like machine of this general type, but provided with another door preferably on the lower front quarter arranged to permit ready unloading of the machine and especially 20 adapted for self-dumping when the inner work holding cylinder is provided with a Y partition arrangement, which is one wherein the cylinder is divided into three pockets or compartments by three partitions extending 25 radially through the cylinder axis; in which arrangement, of course, each pocket formed by these partitions is provided with a peripheral door. It is also obvious that in a certain position one partition becomes inclined 30 downwardly at the front to an extent such that the wet clothes will slide off the partition and if the cylinder door is open and a lower dumping door is provided, automatic dumping may be readily accomplished.

35 In machines of this type, where a tub door is placed below the center, as for dumping purposes, it is essential that such door be properly sealed to prevent water leakage and this is accomplished in the present case by 40 an arrangement of gasket means about the door opening and novel clamping means for sealing the door tightly upon such gasket means to prevent leakage, not only along the lower front edge, but at the sides as well.

45 While the invention has been shown applied to a machine for washing fabrics or clothing and the description hereinafter has particular reference to such a machine, it will be understood that the invention is not thereby limited but is also capable of use in many other machines where the work, whatever it may be, is loaded into and removed from a cylinder which is rotated within an outer casing while subjecting the work to some 50 treatment. For example, it may be used in

dry cleaning washers where the work is rotated in a dry cleaning liquid, such as gasoline; in drying tumblers, where the work is rotated in a current of air; in dyeing machines where the work is rotated in a bath of 55 dye liquor, as well as other like machines of this general type.

Other features of the invention will be readily understood from the accompanying description and drawings, in which:

Fig. 1 is an end elevation of the machine with parts broken away to show details of the structure; Fig. 2 is a front elevation of a portion of the machine with parts broken away; Fig. 3 is a detailed section upon substantially the line 3—3 of Fig. 2; Fig. 4 is a detail of the door sealing mechanism; Fig. 5 is a typical cross section on substantially the line 5—5, Fig. 2, showing the gasket arrangement along the inside edges of adjacent doors; Fig. 6 is a similar view on substantially the line 6—6 of Fig. 2, showing the arrangement of the edges of the end doors; Fig. 7 is a part section on line 7—7 of Fig. 2, showing the manner of mounting the outer door; Fig. 8 is a view in elevation partly broken away to show the locking means for the inner cylinder doors; and Fig. 9 is a detail sectional view on the line 9—9, Fig. 8.

In the drawings, 1 represents the frame end of a machine of a well known construction adapted to support, in any suitable manner not especially shown, the tub sheet 2, which continues around for slightly more than half of the circumference of the tub and terminates at the top and bottom just forward of a vertical plane extending through the axis of the cylinder. If the machine is a multiple pocket machine, it will obviously have a door for each compartment and in whatever arrangement used, there will be guideways for the upper loading door and for the lower unloading door. Customarily, washing machines are of considerable dimension longitudinally and a plurality of both the loading and unloading doors are provided instead of the single one described. In Fig. 2 are shown loading and unloading doors 5^a and 7^a in addition to and corresponding with the doors 5 and 7, and hereinafter such a plurality of doors will be understood although not specifically referred to.

The upper or loading door 5 slides in suitable guides formed by peripheral strips 3 and overhanging strips 4. These strips form

a recess along the edges of the door in which it may slide freely. Since the loading door 5 is above the water line, it is not important that it be packed in any way.

- 5 In the case of the lower or unloading door 7, however, the edges of the tub sheet about the door opening, whether the machine be of single or multiple pocket type, are provided with a gasket 6 preferably of rubber
- 10 in T-shape form arranged to engage the inner side of the unloading door 7 and prevent leakage. The unloading door is held in place against endwise movement, by peripherally extending flanges 8 and against the gasket
- 15 by straps 9 adjustably secured at their upper ends to brackets 10 at the top of the machine and extending down around the front of the machine over the strips 4 and along the side edges of the unloading door 7, and
- 20 at their lower ends are secured to any suitable tightening means.

In the illustrated form of my invention, the tightening means comprise a rock shaft 11 mounted in suitable brackets 11^a, and provided at each strap with a crank arm 12 pivotally connected by pin 13 to the eye 14 of the strap. By this arrangement, when the shaft 11 is moved in a clockwise direction (Fig. 3) the straps are tightened about the 25 unloading door side and clamp the door edges tightly against the gasket 6. It will be noted that the crank arms 12 extend inward toward the tub so that the straps are drawn as snugly as possible about the unloading door.

30 The gasket 6 is continued at 15 across the lower edge of the tub opening and while the straps 9 at the side edges of the unloading door tend to cause the door to seal against this gasket portion 15, additional means is 35 provided for ensuring a proper sealing at this point. This is accomplished by means of a rocking counter-shaft 16 mounted in bearings 17 secured to the brackets 11^a and provided between the straps 9 with eccentricities 16^a adapted to be rotated into engagement with the door to force its lower edge against the gasket portion 15.

35 The rock shaft 16 projects beyond the end of the machine and is there provided with a worm wheel 18 meshing with a worm 19 carried by a shaft 20 mounted in a suitable bracket 21. Shaft 20 is provided with a hand wheel 22 for rotating it. The rock shaft 16 is further provided with a crank 40 arm 23 connected by a curved link 24 with the upper end of a lever 25 secured upon the shaft 11.

45 The link 24, the arm 23 and the eccentricities 16^a are so arranged that the throw of the arm 23 is sufficient to move the lever 25 and tighten the bands to substantially their maximum tension before the eccentricities 16^a reach their position of maximum pressure so that the final movement of the arm 23 is into 50 aligned position with respect to the pivotal

connection of the link 24 with the arm 25. This toggle arrangement and effect permits considerable movement of the arm 23 for bringing the eccentricities to final pressure position without further material movement of the lever or arm 25. It is employed because it permits tightening of the straps 9 to their maximum clamping position and also permits required movement of the eccentricities to accomplish their clamping function.

55 The weight of the unloading door may be counter balanced by use of chains 26 and counter weights 27 extended over suitable pulleys or rollers 28 on the frame of the machine.

60 Rotatably mounted in the tub is a cylindrical container comprising perforated end heads 30 and a perforated cylindrical wall 31 connected therebetween. This cylindrical wall has openings 32 each provided with a sliding door 33 held in place by lock bolts 33^a slidably mounted in a lock casing 34. The bolt is normally pressed outward by a spring 35 and is retracted by gear teeth 36 on a handle lever 37, meshing with rack teeth 38 on the bolt. There are usually two of these lock bolts near the lower front edge of each door 33, arranged to enter suitable keeper openings 39 formed in the cylindrical wall corresponding with open and closed 65 positions of the doors 33.

65 The cylindrical container may have transverse partitions in it and it may also be provided with longitudinal partitions 40 separating it into three lengthwise compartments, in which instance the partitions are of Y formation. In any event there is a door for each of the partition formed compartments. When the radial partitions 40 are used, it is obvious that the front lower edge of each 70 door 33 should close adjacent to a partition so that the contents of the compartment may slide out unobstructed when the door is opened.

75 In operation, assuming the tub doors open, the operator through any mechanism, not shown, causes the inner container to rotate until the door 33 of one of the compartments is in a position to be opened. Upon opening the compartment door, he may now charge 80 or load the materials to be treated into the compartment, reclose said compartment door and then proceed in a similar manner to load the remaining compartments in succession.

85 After all compartments are loaded and the 90 compartment doors have been closed, the operator raises the unloading door 7 to closed position and by turning the hand wheel 22, clamps said door watertight in this position. The loading door 5, is then lowered into 95 closed position, and the machine is started in the treating operation, such as washing, dry cleaning, drying or tumbling, dyeing or the like.

100 Upon completion of the treating process, 105

the machine is stopped, the tub loading door is opened, the tub unloading door is released and opened, and the nearest cylinder door is opened. The cylinder is then rotated in a counter clockwise direction (Fig. 3) until the contents of the corresponding compartment are caused to slide out of the machine. The remaining compartments are emptied in a similar manner.

10 What I claim is:

1. In a washing or like machine, a stationary cylindrical tub provided with an opening, a sliding door for said opening, and flexible clamping means engaging the side portions 15 of said door, throughout the entire extent of the door sides for sealing the door against the tub at the sides of said opening.

2. In a washing or like machine, a stationary cylindrical tub provided with an opening, a sliding door for said opening, and flexible clamping straps for sealing the sides 20 of said door against the tub at the sides of said opening.

3. In a washing or like machine, a cylindrical tube provided with an opening, a sliding door for said opening, flexible straps for sealing the sides of said door against the tub at the sides of said opening, and rotatable means for sealing the bottom of said door 25 against said tub at the bottom of said opening.

4. In a washing or like machine, a cylindrical tub provided with an opening, a sliding door for said opening, and eccentric means 30 engaging said door for sealing the bottom of said door against the tub at the bottom of said opening.

5. In a washing or like machine, a cylindrical tub provided with an opening, a sliding door for said opening, flexible straps for sealing the sides of said door against the tub at the sides of said opening, and eccentric means for sealing the bottom of said door against said tub at the bottom of said opening, said means 40 being distributed along the lower edge of the door.

6. In a washing or like machine, a cylindrical tub provided with an opening, a sliding door for said opening, flexible means for seal-

ing the sides of said door against the tub at 50 the sides of said opening, and rotatable means distributed along the lower edge of the door cooperating therewith for sealing the bottom of said door against the tub at the bottom of said opening.

7. In a washing or like machine, a cylindrical tub provided with an opening, a sliding door for said opening, tension operated means for sealing the sides of said door against the tub at the sides of said opening, rotation operated means for sealing the bottom of said door against said tub at the bottom of said opening, and operating means for said sealing means, whereby said tension is substantially 55 accomplished before said rotation.

8. In a washing or like machine, a cylindrical tub provided with an opening, a sliding door for said opening, tension operated means for sealing the sides of said door against the tub at the sides of said opening, rotation operated means for sealing the bottom of said door against said tub at the bottom of said opening, and operating means common to both of said sealing means, whereby substantially 60 said tension is accomplished before said rotation.

9. In a washing or like machine, a cylindrical tub provided with an opening, a sliding door for said opening, shaft operated means for sealing the bottom of said door against the 65 tub at the bottom of said opening, counter-shaft operated means for sealing the sides of said door against said tub at the sides of said opening, said shafts being interconnected.

10. In a washing or like machine, a cylindrical tub provided with an opening, a sliding door for said opening, shaft operated means for sealing the bottom of said door against the tub at the bottom of said opening, counter-shaft operated means for sealing the sides of 70 said door against said tub at the sides of said opening and connecting means between said shafts such that sealing motion of said shaft is substantially preceded by sealing motion of said countershaft.

In testimony whereof I hereby affix my signature.

FORREST J. COUCH.

CERTIFICATE OF CORRECTION.

Patent No. 1,682,116.

Granted August 28, 1928, to

FORREST J. COUCH.

It is hereby certified that error appears in the printed specification of the above numbered patent requiring correction as follows: Page 3, line 25, claim 3, for the word "tube" read "tub"; same page, line 37, claim 4, after the word "opening" and before the period insert a comma and the words "said means being distributed along the lower edge of the door"; same page, line 42, claim 5, after the word "means" insert the words "distributed along the lower edge of the door"; lines 44 to 46, same claim, strike out the comma and words ", said means being distributed along the lower edge of the door"; line 52, claim 6, strike out the words "distributed along the lower edge of the door"; and the said Letters Patent should be read with this correction therein that the same may conform to the record of the case in the Patent Office.

Signed and sealed this 23rd day of October, A. D. 1928.

(Seal)

**M. J. Moore,
Acting Commissioner of Patents.**
